UNITED STATES PATENT OFFICE.

HARVEY M. ORCUTT, OF WARSAW, INDIANA.

SPRING-FASTENING FOR HARNESS.

SPECIFICATION forming part of Letters Patent No. 244,475, dated July 19, 1881.

Application filed May 31, 1881. (Model.)

To all whom it may concern:

Be it known that I, HARVEY M. ORCUTT, of Warsaw, in the county of Kosciusko and State of Indiana, have invented certain new and useful Improvements in Spring-Fastenings for Harness, &c.; and I do hereby declare that the following is a full, clear, and exact description of the invention, which will enable others skilled in the art to which it appertains to make and use the same, reference being had to the accompanying drawings, which form a part of this specification.

Figure 1 is a plan view of my improved buckle or snap. Fig. 2 is a longitudinal sectional view of the same. Fig. 3 is a horizontal sectional view; and Fig. 4 is a detail view, showing the several parts detached from each other.

Corresponding parts in the several figures are denoted by like letters of reference.

This invention relates to spring-fastenings for harness, &c.; and it consists in certain improvements in the construction of the same, which will be hereinafter fully described, and particularly pointed out in the claim.

In the drawings hereto annexed, A represents a suitable metallic casing, the under side of which is provided at the rear end with a recess, B, in which one end of any harness-strap, in connection with which the device is to be employed, may be riveted or otherwise secured. The front end of casing A is divided by a vertical partition, C, from the main body of said casing, which is lettered D, in contradistinction to the front chamber, E. The upper and lower sides of the chamber D are slotted longitudinally to admit a stem, F, forced

in a forward direction by a spring, G, placed in said chamber D. The stem F carries at its upper end a covering-plate, H, sliding on top of the casing A. The front chamber, E, of the said casing, which is open on top, is closed by the slide H. The front side of the chamber E of casing A has a vertical slot, I, to receive the shank J of a T-shaped hook, the cross-piece of which, K, is adjustable in the chamber E and retained in position by the slide H. The T-shaped hook J K is, of course, to be suitably attached to the harness or other strap which is to be connected to the strap to which the casing A is permanently attached.

This invention is simple, inexpensive, convenient, and easily operated, and the parts connected by this spring-fastening can never become accidentally separated, except by breakage, which is practically prevented by the strength and solidity of the component parts.

Having thus described my invention, I claim and desire to secure by Letters Patent of the United States—

The combination, with the casing A, having longitudinally-slotted upper and lower sides, partition C, vertical slot I, spring G, stem F, and cover H, of the T-shaped hook J K, substantially as herein described, for the purpose shown and specified.

In testimony that I claim the foregoing as my own I have hereto affixed my signature in presence of two witnesses.

HARVEY M. ORCUTT.
